UNITED STATES PATENT OFFICE.

WILLIAM REEVES, OF NEW HAVEN, CONNECTICUT.

EYE-CLEANSING DEVICE.

No. 846,142.

Specification of Letters Patent.

Patented March 5, 1907.

Application filed April 14, 1906. Serial No. 311,684.

To all whom it may concern:

Be it known that I, WILLIAM REEVES, a citizen of the United States, residing at New Haven, in the county of New Haven and State of Connecticut, have invented certain new and useful Improvements in Eye-Cleansing Devices, of which the following is a specification, reference being had therein to the accompanying drawings.

My invention relates to new and useful improvements in eye-cleansing devices, and has for its object, among other things, the production of a device which will remove dirt, chips, or other foreign particles from the eye and to accomplish this result with mechanism that will be simple in construction, neat and pleasing in appearance, and manufactured at the minimum cost.

To these and other ends my invention consists in the eye-cleansing device having certain details of construction and combinations of parts, as will be hereinafter described, and more particularly pointed out in the claims.

Referring to the drawings, in which like numerals of reference designate like parts in the several figures, Figure 1 is a perspective view of my device complete, and Fig. 2 is an elevation of a modified form of tip.

In the practice of my invention I provide a funnel-shape hood 1, having a flexible tube 2 connected therewith at its smaller end, and a tip 3, having an aperture therethrough fixed in the opposite end of said tube. The air is drawn through the tip 3, tube 2, and hood 1 by any convenient form of mechanism; but I prefer to use the device shown in Fig. 1, which consists of a motor 4, of any preferred form, fixed upon a base 5 and having a fan 6 secured to its armature-shaft 7, which fan is rotatable within the larger end of the hood 1. This motor is operated from a conveniently-located battery 8.

In operation the fan is rotated by starting the motor, the eyelid is folded back, and the tip 3 moved in front of and adjacent the eyeball. All of the dirt and particles in the eye will be drawn by suction out of the eye

through the tip 3. The tip 3 is preferably magnetized; so as to more readily remove steel or iron chips. In some cases the foreign matter might be embedded in the eye in such a manner as not to be removable by suction alone, and in these cases I prefer to substitute for the tip 3 the modified form of tip 9, the front end of which is beveled, so as to form a projecting lip 10, that can be so manipulated as to cut under the foreign matter and loosen it from its bed in the eyeball, after which it may be taken up by suction.

What I claim as new, and desire to secure by Letters Patent, is—

1. In a device of the character described, the combination with a base; of a hood connected therewith; rotary suction means in said hood; and a flexible tube having an apertured tip connected with one end thereof and secured to said hood.

2. In a device of the character described, the combination with a hood having an aperture through one end thereof of less diameter than the other end of said hood; of rotary suction means operative in the larger end of said hood; a flexible tube connected at one end with said hood; and an apertured tip fixed in the opposite end of said tube.

3. In a device of the character described, the combination with a base; of a funnel-shape hood connected therewith; means, as a rotating fan, in the larger end of said funnel, for producing a suction therethrough; and a flexible tube having an apertured tip connected with one end thereof and secured to said hood.

4. In a device of the character described, the combination with a base 5; of the hood 1; a motor 4; a fan 6 rotated thereby; a flexible tube 2 connected with said hood; and an apertured tip fixed in one end of said tube.

In testimony whereof I affix my signature in presence of two witnesses.

WILLIAM REEVES.
